US0D1108869S

(12) United States Design Patent (10) Patent No.: US D1,108,869 S
(45) Date of Patent:  Jan. 13, 2026

(54) GRILL

(71) Applicant: Doc Konto, Ltd, Middlesex (GB)

(72) Inventor: Alexander Kontoghiorghes, London (GB)

(73) Assignee: Doc Konto, Ltd, Middlesex (GB)

() Term: 15 Years

(21) Appl. No.: 29/963,893

(22) Filed: Sep. 19, 2024

(51) LOC (15) Cl. 07-02

(52) U.S. Cl.

USPC D7/334

(58) Field of Classification Search

(57) CLAIM

The ornamental design for a grill, as shown and described.

DESCRIPTION

FIG. 1 is a top, front, left-side perspective view of a grill showing the new design;

FIG. 2 is a bottom, back, right-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the grill that form no part of the claimed design. The dot-dashed broken lines represent boundaries of the claimed design and form no part of the claimed design.

1 Claim, 8 Drawing Sheets
